UNITED STATES PATENT OFFICE.

ERNEST A. NIELSEN AND FREDERICK C. PETERSEN, OF EAST BOSTON, MASSACHUSETTS.

DESIGN FOR A CANDLESTICK OR SIMILAR ARTICLE.

40,778.

Specification for Design.

Patented July 19, 1910.

Application filed April 27, 1910. Serial No. 558,091. Term of patent 3½ years.

To all whom it may concern:

Be it known that we, ERNEST A. NIELSEN and FREDERICK C. PETERSEN, subjects of the King of Denmark, residing at East Boston, in the county of Suffolk and State of Massachusetts, have invented a new, original, and ornamental Design for Candlesticks or Similar Articles, of which the following is a specification, reference being had to the accompanying drawings, forming a part thereof.

The figure is a perspective view of a candle-stick or similar article, showing our design.

We claim:

The ornamental design for a candle-stick or similar article as shown.

ERNEST A. NIELSEN.

FREDERICK C. PETERSEN.
